DESIGN FOR A STOCKING

William N. Minkel, Milwaukee, Wis., assignor to
Phoenix Hosiery Company, Milwaukee, Wis., a
corporation of Wisconsin

Application October 16, 1939, Serial No. 87,689

Term of patent 7 years

To all whom it may concern:

Be it known that I, William N. Minkel, a citizen of the United States, residing at Milwaukee, in the county of Milwaukee and State of Wisconsin, have invented a new, original, and ornamental Design for a Stocking, of which the following is a specification, reference being had to the accompanying drawing, forming a part thereof, and in which:

Figure 1 is a side elevation of the stocking embodying my design, and

Figure 2 is an enlarged detailed view of the cuff thereof.

The characteristic feature of the design resides

in the cuff portion of the stocking embodying the herringbone appearance as shown. Except for the conventional seam up the back of the leg, which also extends through the cuff portion, the cuff portion is of uniform appearance throughout its circumferential extent so that the appearance of the opposite side of the stocking from that shown in the figures of the drawing is the same as the portion illustrated.

I claim:

The ornamental design for a stocking, as shown and described.

WILLIAM N. MINKEL.
